DESIGN FOR LEATHER

Hans Hiedemann, Cologne, Germany, assignor, by
mesne assignments, to R. Neumann & Com-
pany, Hoboken, N. J., a corporation of New
Jersey

Application May 3, 1935, Serial No. 56,671

Term of patent 7 years

To all whom it may concern:

Be it known that I, Hans Hiedemann, a citizen
of Germany, residing at Cologne, Germany, have
invented a new, original, and ornamental Design
for Leather, of which the following is a specifica-
tion, reference being had to the accompanying
drawing, forming a part thereof.

The figure of the drawing is a plan view of a
piece of leather embodying my design, the design

unit of which is indicated by the dot and dash
lines.

The design is characterized by the dots which
are indented in the fabric outlining the several
elements composing the complete design.

I claim:—

The ornamental design for leather substan-
tially as shown and described.

HANS HIEDEMANN.
